US0D1074810S

(12) **United States Design Patent** (10) **Patent No.:** **US D1,074,810 S**
Albuzat et al. (45) **Date of Patent:** **** May 13, 2025**

(54) **TAG FOR SUPPLEMENTAL TYPE CERTIFICATION**

(71) Applicant: **Swift Fuels, LLC**, West Lafayette, IN (US)

(72) Inventors: **Thomas Albuzat**, West Lafayette, IN (US); **Jonathon D. Ziulkowski**, West Lafayette, IN (US)

(73) Assignee: **Swift Fuels, LLC**, West Lafayette, IN (US)

(**) Term: **15 Years**

(21) Appl. No.: **29/854,921**

(22) Filed: **Sep. 29, 2022**

(51) **LOC (15) Cl.** **19-08**

(52) **U.S. Cl.** **D20/22**
USPC .....

(58) **Field of Classification Search**
